UNITED STATES PATENT OFFICE

2,466,969

COTTON PICKING MACHINE

Mack D. Rust, Phoenix, Ariz.

Application December 11, 1944, Serial No. 567,651

14 Claims. (Cl. 56—41)

1

My invention relates to cotton picking machines of the Rust type, see Patents Nos. 2,058,514 issued October 27, 1936, 2,076,598 issued April 13, 1937, and 2,085,046 issued June 29, 1937, for examples.

In a machine of the Rust type there is provided a main frame of elongated construction having a middle space or chamber; at the ends of this frame sprocket shafts are mounted about which shafts and the frame run upper and lower conveyor chains carrying slats on which are mounted picking spindles. The spindles have rollers which run on tracks mounted on the outside of the working side of the frame; the working side of the frame is outwardly curved while the opposite side is straight in the usual construction. The backing members for the tracks are mounted on the frame between it and the slatted conveyor.

Heretofore, when it has become necessary to replace a track or tracks, it was necessary to partially dis-assemble the conveyor in order to get at the tracks. This was a tedious and time consuming operation often keeping the machine out of commission for several hours. It is therefore the principal object of the present invention to provide means for eliminating this objectionable feature and to provide means whereby the tracks and their backing members can be quickly and conveniently removed and replaced without disturbing the conveyor and without having to put the machine out of commission for any considerable length of time.

Again, it is an object to provide separate track backing members for groups of two or more horizontal rows of spindles and to make each track backing member removable and replaceable via the chamber of the frame without disturbing the spindle conveyor or any of the other track backing members, thereby making it possible to remove and replace the damaged track in a minimum of time and with the least inconvenience.

Other objects will in part be obvious and in part be pointed out hereinafter.

To the attainment of the aforesaid objects and ends the invention still further resides in the novel details of construction, combination and arrangement of parts, all of which will be first fully described in the following detailed description, and then be particularly pointed out in the appended claims, reference being had to the accompanying drawings, in which:

Fig. 1 is a part horizontal section taken approximately on the line 1—1 of Fig. 2, and a part plan view of the main frame of a Rust cotton

2

picker and the adjacent picker spindles and slats on the working side of the frame.

Fig. 2 is a detail section on the line 2—2 of Fig. 1.

Fig. 3 is an enlarged horizontal section and part plan view of a portion of the structure shown in Fig. 1, taken on the line 3—3 of Fig. 4.

Fig. 4 is an enlarged vertical cross section on the line 4—4 of Fig. 3, the parts 40, 34, 43 in the lower half of the figure being shown in the position these parts occupy when moved to the position indicated by the dotted lines in Fig. 1.

Fig. 5 is an elevation of the tubular post and the adjacent ends of two track backing members, parts being broken away.

Fig. 6 is a section on the line 6—6 of Figure 5.

Fig. 7 is a detail perspective view hereinafter again referred to.

Fig. 8 is a detail horizontal sectional view on approximately the line 4—4 of Fig. 3 hereinafter again referred to.

Fig. 9 is a detail view similar in part to Fig. 1, showing a modified construction.

Fig. 10 is a section on the line 10—10 of Fig. 9.

Fig. 11 is a section on the line 11—11 of Fig. 10.

Fig. 12 is an enlarged detail section of the rear portion of the spindle backing, taken in the plane 30 of the line 12—12 of Fig. 13.

Fig. 13 is a fragmentary detail elevation of a portion of the structure shown in Fig. 12 looking in the direction of the arrow in Fig. 12.

Fig. 14 is a detail view showing how the post 35 21^a is vertically adjustably mounted.

In the drawings in which like numbers of reference indicate like parts in all the figures, the main frame is shown constructed of two end channel posts 1 and 2 connected along one side 40 by upper and lower angle irons 5 and 3, respectively. On the front or working side of the frame are upper and lower curved angle bars 6 and 4, respectively. The bars 6 and 4 cooperate with other fixed angle bars 10 and 11, respectively, to carry the roller-chain tracks 14, for the slatted conveyor (12, 13, 15).

The bars 5 and 6 are connected by a cross bar 7 about midway the ends of the frame, the bars 3 and 4 are connected by a cross bar 7^x. Filler plates 9 are welded to the bars 3, 4 and 5, 6 respectively at their ends. The channel posts 1 and 2 are welded to the bars 3, 4, 5, 6, and to the plates 9, 9^x and together with the back plate 8 constitute the principal elements of the main frame of the machine.

The spindle carrier comprises upper and lower endless chains composed of links 12 and rollers 13 which run on tracks 14 secured to the angle bars 4 and 6 of the frame and other angle bars 10 and 11 suitably fixedly supported (not shown) from the frame in a well known manner (see patents aforementioned). Slats 15 are mounted on the chains in the usual manner and carry the picking spindles 16 whose rollers 17 engage tracks 18 mounted on the outer side of the frame. In the preferred embodiment of the invention there is provided one track for each two horizontal rows of spindles although if desired a separate track for each row may be provided.

Each track 18 has a neck 19 and a head 20 similar to the neck and head shown in Fig. 5 of Patent No. 2,058,514 aforesaid.

The post 21 is provided with a keyhole slot 22 to receive the neck and head of the track 18, see Figs. 3 and 4. The post 21 is welded to the rails 4 and 6 and to the plates 9 at the front of the frame and also serves as a part of the frame. At the rear of the center of the frame a hollow post 28 is welded to the rails 4 and 6 and serves in part to stiffen the frame and in part as a means by which the track backings are mounted on the frame as will be more clearly understood later.

The track backing members each comprises a longitudinal bar against which the track 18 lies and is pressed by the spindle rollers during the operation of the machine. Preferably this track backing member is made in two sections, a back section 23 and a front section 32. The back section 23 extends rearwardly from the post 28 with which it is endwise slidably connected in any suitable manner, preferably by means of a dovetail block 24 welded or otherwise suitably secured to the back face of the bar, the dovetail 24 fitting between dovetailed blocks similarly secured on the front face of the post 28, see Figs. 5 and 6. The bar 23 has a lug 26 which when the bar is in place engages a lug 27 fixed to the post 28 to limit the rearward movement of the bar as it is inserted in place. In lieu of the lugs 26, 27 or in addition to them I may provide stop shoulders on the rear dovetail blocks 29 that are carried by the bar 23 and fit dovetail slots in a vertical support 31 that is secured to the channel post 2, see Figs. 1 and 7. The dovetail blocks 29 have reduced dovetails 30 to fit the slots of the post 31.

The rear track backing member 23 is also preferably provided at about its mid-length with another dovetail block 24 to fit dovetail guides, similar to the guides 25, on the angle post 45 that is welded to the bars 4 and 6. It should be understood that the intermediate and rear dovetails are preferably made progressively smaller than the front one so as to slide freely through the front one in removing and replacing the member 23 as will more clearly appear presently.

The front section of the track backing member, at its rear end has a dovetail block 50 corresponding to block 24 and fitting the dovetail guides 25 of the post 28, see Figs. 1 and 5. At its forward end the bar 32 is slit as at 33 to provide a tongue 34 which is bent inwardly as best shown in Fig. 1. This provides a support for the neck of the track 18. The front plate 36 which is welded or otherwise secured to the front end of the bar 32 is slotted, as at 42, to permit the neck 19 to pass so that the head 20 may lie in front of the post 21 while the neck lies in the narrow part of the keyhole slot 22,

see Figs. 3 and 4. Since the front section of the track backing member receives the greater strain I provide a truss in the form of a channel beam 35 which is welded to the back of the bar section 32 and extends from end to end of the same.

The plate 36 has stop notches 37 to engage the stop lugs 38 on the post 21 to limit the outward movement of the bar 32 to a position to line up with the rear section 23 when in place.

Pivoted between ears 39 on the back of the truss 35 is a toggle latch 40 held in either of two positions by a spring 41. The hinged end of the latch rests in a saddle 48 and has an elongated pin hole 47 for the hinge pin 46 so that the thrust is not applied to the pin but against the saddle. When the latch is in the normal or latching position (Figs. 1 and 3) its free end 40 lies in the larger part of the keyhole slot 22 and presses against the inner flange of the post 21 thereby holding the bar 32 at its front end against getting loose due to vibrations of the machine when in use. The spring 41 constantly tends to tighten the bar in place and to that end the curved free end of the latch is preferably made eccentric to the pivot 46.

The outer faces of the bar sections 23 and 32 are provided with wear strips of any suitable material as for example fibre. These strips 43 are secured to the bars in any suitable way and constitute, functionally, a continuation of the guide plate 44 that is fixed to the frame in the usual manner.

The track 18 may be made of any suitable material and per se is not of the present invention. The tracks may be made as disclosed in Patent No. 2,058,514 aforesaid if desired.

With the parts in the position shown in Figs. 1 and 3 and the upper part of Fig. 4, in order to remove the track backing member and its track, the operator reaches down into the chamber X of the frame and throws back the latch 40 to the position shown in dotted lines in Fig. 1 where it is held by toggle spring 41. He then pulls in the front end of the member 32 using its rear end somewhat as a pivot and lifts that section out of the machine. He next moves the rear section 23 from right to left in Fig. 1 until it comes into the place where the front section was and then he swings it inwardly as he did the front section and lifts the back section up out of the machine. The track 18 is now exposed and the attendant reaches in, unhooks the head and pulls the track forward and out through the chamber X.

To replace the track or place a new track the above operations are reversed. First the track is put into place, then the rear section of the member 23 is replaced and finally the front section is put in and snapped into locked position by throwing the latch forward again.

In Figs. 9 to 14 inclusive I have shown a modification of my invention. In these figures those parts which correspond to similar parts in the preceding figures bear the same reference numbers plus the index letter a.

In this embodiment of my invention the track backing member front section 32a is made of simple flat bar steel rolled and formed to shape required. It is not provided with the channel shaped reinforcing truss 35 and has, as support in lieu thereof, two removable posts 54. These two vertical posts 54 are attached to the top and bottom frame members 4 and 10 by means of cap screws 56 and tapped mounting blocks or brackets

55 welded to members 4 and 10. They can be quickly removed when desired to gain access to the drive elements.

The locking device, corresponding to the toggle latch 40, is a simple wedge 53 shown in Figs. 9, 10, and 11. In practice, the wedge 53 has been found easy to make and so far has given no trouble whatever. To lock the track backing member in position, the wedge is dropped into place between lugs 51 and 52 as shown and tapped 10 lightly downward with a hammer or any suitable tool, and to remove same the reverse applies. Tapping the wedge from below to loosen and removing same permits the front end of the track backing member's front section to be swung inwardly for removal from its working position. Prior to removal of any track backing member section, however, it is necessary with this construction to remove both of the vertical posts 54.

The front support post 21^a is constructed as a tubular member rather than as a channel-shape member, but it is provided with the same general arrangement of key hole slots 22^a to receive the neck and head of the track 18. This post is bolted to the top and bottom rails and can be removed or adjusted vertically if necessary by use of cap screws 56 and slotted brackets 55^a welded to the top and bottom bars. It is not relied on to perform as a stiffening member for the main frame, although of course this member when bolted into position does naturally supplement the strength of the main frame structure.

Arrangement of the mid-post 28^a is shown in Figs. 9 and 12. It includes an angle in place of the tube previously shown. Instead of the tapered dovetail connections heretofore shown, there is used a flat bar 57 (Figs. 9, 12 and 13) welded to track backing member 32^a, which jointly engage the lugs on notched bar 58 bolted to post 28^a. The extreme rear end of backing member 32^a will be seen to rest against a portion of the notched bar 63 which is also bolted to the other leg of post angle 28^a. Member 32^a is thus held at the rear against movement in all directions except pivoting and forwardly, which motions permit proper removal when desired. The bar 58 has short legs 59 between which the rear ends of the members 32^a lie. The bar 63 also has short legs 64 between which the front ends of members 23^a lie.

The rear section 23^a of the track backing member is supported vertically and against inward motion at the front by notched bar 63 with the bent lugs 64 as shown in Fig. 12. The rear end of member 23^a is supported vertically and against inward movement by the notched angle post 61 which is secured to main frame post member 2^a by cap screws 56. Member 23^a is held against outward and longitudinal motion by means of a cap screw 56 passing through angle 60 and threaded into member 23^a. Angle 60 is secured to post 45^a by bolts 62 and is capable of adjustment as necessary vertically or laterally by means of suitably placed slotted bolt holes.

I have found in practice that it is possible to remove and replace the tracks without removing the rear section of the track backing member. In all cases so far it has only been necessary to remove the front section of the track backing member in order to remove the tracks themselves.

From the foregoing description taken in connection with the accompanying drawings it is thought the complete construction and operation as well as the advantages of the same will be clear to those skilled in the art.

While I have disclosed a preferred embodiment of the invention I wish it understood that numerous changes in the details of construction can readily be made by those skilled in the art without departing from the spirit of the invention within the scope of the appended claims.

What I claim is:

1. In a cotton picking machine wherein is provided a main frame around and adjacent which travels an endless slatted spindle carrier on which horizontal rows of spindles having rollers are mounted, said frame having a chamber, there being a track for each two horizontal rows of spindles on which track the rollers run; the improvement which includes a track-backing bar for each track, said bar comprising a front section and a back section held end to end, a support for the front end of the front section, a support for the rear end of the back section, and a support for the adjacent ends of the bar sections, and means to mount said bar sections on said supports.

2. In a cotton picking machine wherein is provided a main frame around and adjacent which travels an endless slatted spindle carrier on which horizontal rows of spindles having rollers are mounted, said frame having a chamber, there being a track for each two horizontal rows of spindles on which track the rollers run; the improvement which includes a track-backing bar for each track, said bar comprising a front section and a back section held end to end, a support for the front end of the front section, a support for the rear end of the back section, a support for the adjacent ends of the bar sections, and means to mount said bar sections on said supports, said adjacent-ends-support being located on the chamber side of said bar and said bar sections being endwise slidably held on the support by their mounting means.

3. In a cotton picking machine wherein is provided a main frame around and adjacent which travels an endless slatted spindle carrier on which horizontal rows of spindles having rollers are mounted, said frame having a chamber, there being a track for each two horizontal rows of spindles on which track the rollers run; the improvement which includes a track-backing bar for each track, said bar comprising a front section and a back section, means for mounting said bar sections in endwise alignment on said frame, said mounting means including a support on the frame for the rear end of the back section, a support for the adjacent ends of the bar sections which support includes bar holding elements through which the rear bar section may be endwise displaced into the space normally occupied by the front section of the bar after that section shall have been removed, and means releasably supporting the front end of the front section of the bar.

4. In a cotton picking machine wherein is provided a main frame around and adjacent which travels an endless slatted spindle carrier on which horizontal rows of spindles having rollers are mounted, said frame having a chamber, there being a track for each two horizontal rows of spindles on which track the rollers run; the improvement which includes a track-backing bar for each track, said bar comprising a front section and a back section, means for mounting said bar sections in endwise alignment on said frame, said mounting means including a support on the frame for the rear end of the back section, a support for the adjacent ends of the bar sections which support includes bar holding elements

through which the rear bar section may be endwise displaced into the space normally occupied by the front section of the bar after the front section shall have been removed, a support for the front end of the front bar section which support includes a stop limiting the outward movement of said front end and means for holding the bar against said stop to prevent accidental inward movement of said front end.

5. In a cotton picking machine wherein is provided a main frame around and adjacent which travels an endless slatted spindle carrier on which horizontal rows of spindles having rollers are mounted, said frame having a chamber, there being a track for each two horizontal rows of spindles on which track the rollers run: the improvement which includes a track-backing bar for each track, said bar comprising a front section and a back section, means for mounting said bar sections in endwise alignment on said frame, said mounting means including a support on the frame for the rear end of the back section, a support for the adjacent ends of the bar sections which support includes bar holding elements through which the rear bar section may be endwise displaced through the space normally occupied by the front section of the bar after that section shall have been removed, and means releasably supporting the front end of the front section of the bar, the last named means comprising a spring-loaded latch device engaging said front end support and continuously forcing the front end of the front bar section against its stop.

6. In a cotton picking machine wherein is provided a main frame around and adjacent which travels an endless slatted spindle carrier on which horizontal rows of spindles having rollers are mounted, said frame having a chamber, there being a track for each two rows of spindles on which track the rollers run: the improvement which includes a sectional bar for supporting said track, said bar including at least a front section and a back section held in longitudinal alignment, a support for the adjacent ends of the sections, an intermediate support for the back section, means to mount said back section on its support for endwise movement of the bar section, means limiting the rearward movement of said back section in its supports, and means to support the front section of the bar.

7. In a cotton picking machine wherein is provided a main frame around and adjacent which travels an endless slatted spindle carrier on which horizontal rows of spindles having rollers are mounted, said frame having a chamber, there being a track for each two horizontal rows of spindles on which track the rollers run: the improvement which includes a sectional bar for backing said track, said bar including at least a front section and a back section held in longitudinal alignment, a support for the adjacent ends of the sections, an intermediate support for the back section, means to mount said back section on its support for endwise movement of the bar section, means limiting the rearward movement of said back section in its supports, and means to support the front section of the bar, said last named means including elements on the support for the front end of said front section to hold said front end against up and down movement and limiting its movement toward said track and said carrier, and releasable means constantly urging said front end outwardly toward said track and said carrier.

8. In a cotton picking machine wherein is pro-

vided a main frame around and adjacent which travels an endless slatted spindle carrier on which rows of spindles having rollers are mounted, said frame having a chamber, there being a track for each two rows of spindles on which track the rollers run: the improvement which includes a sectional bar for supporting said track, said bar including at least a front section and a back section held in longitudinal alignment, a support for the adjacent ends of the sections, an intermediate support for the back section, means to mount said back section on its supports for endwise movement of the back section, means limiting the rearward movement of said back section in its supports, and means to support the front section of the bar, said front section having a longitudinal slot with an inwardly bent tongue to receive the front end of said track, said support for the front section having a keyhole slot for the reception of the front extremity of the track and anchor same.

9. In a cotton picking machine wherein is provided a main frame around and adjacent which travels an endless slatted spindle carrier on which rows of spindles having rollers are mounted, said frame having a chamber, there being a track for each two rows of spindles on which track the rollers run: the improvement which includes a sectional bar for supporting said track, said bar including at least a front section and a back section held in alignment longitudinally, a support for the adjacent ends of the sections, an intermediate support for the back section, means to mount said back section on its support for endwise movement of the back section, means limiting the rearward movement of said back section in its support, and means to support the front section of the bar, said front section having a longitudinal slot with an inwardly bent tongue to receive the front end of the track, said support for the front section having a keyhole slot for the reception of the front part of the track and anchor same, the rear end of said front section of track being mounted so that the front end of said front section can be swung inwardly into said chamber on said rear end as a pivot.

10. In a cotton picking machine wherein is provided a main frame around and adjacent which travels an endless slatted spindle carrier on which rows of spindles are mounted and having rollers, said frame having a chamber, there being a track for each two horizontal rows of spindles on which track said rollers run: the improvement which includes a sectional bar for supporting said track, said bar including at least a front and a back section in longitudinal alignment, a support for the adjacent ends of said sections, means to mount said back section on its supports for endwise movement of that section, means limiting the rearward movement of said back section in its supports, and means to support the front section of the bar, said front section having a longitudinal slot with an inwardly bent tongue to receive the front end of said track, said support for the front section having a keyhole slot for the reception of the front end of said track and anchor same, the rear end of said front section being mounted so that the front end thereof can be swung inwardly into said chamber on said rear end of the section as a pivot.

11. In a cotton picking machine in which is provided a frame around and adjacent which travels an endless slatted spindle carrier on

which horizontal rows of spindles having rollers are mounted, there being a track for each two rows of spindles on which track the rollers run: the improvement which includes a sectional backing bar for said track, said bar including at least a front section and a back section in longitudinal alignment, a support for the adjacent ends of said sections, a support for the front and the back ends, respectively, of said bar, means to mount the back section of the bar on its supports for endwise movement, means limiting the rearward movement of said back section in its supports, and a truss secured to the back face of said front section of said bar.

12. In a cotton picking machine wherein is provided a main frame around and adjacent which travels an endless slatted spindle carrier on which horizontal rows of spindles having rollers are mounted, said frame having a chamber, there being at least one track for each two horizontal rows of spindles on which track the rollers run: the improvement which includes a track-backing member for each track, said member comprising a front section and a back section, means for mounting said member sections in endwise alignment on said frame, said mounting means including a support on the frame for the rear end of the back section, a support for the adjacent ends of the sections which support includes holding elements through which the rear section may be endwise displaced into the space normally occupied by the front section after the front section shall have been removed, a support for the front end of the front section which support includes a stop limiting the outward movement of said front end and means for holding said front end against said stop to prevent accidental inward movement of said front end.

13. In a cotton picking machine wherein is provided a main frame around and adjacent which travels an endless slatted spindle carrier on which horizontal rows of spindles having rollers are mounted, said frame having a chamber, there being at least one track for each two horizontal rows of spindles on which track the rollers run: the improvement which includes a track-backing member for each track, said member comprising a front section and a back section, means for mounting said member sections in endwise alignment on said frame, said mounting means including a support on the frame for

the rear end of the back section, a support for the adjacent ends of the sections which support includes holding elements through which the rear section may be endwise displaced into the space normally occupied by the front section after the front section shall have been removed, a support for the front end of the front section which support includes a stop limiting the outward movement of said front end and means for holding said front end against said stop to prevent accidental inward movement of said front end, said last named means comprising a lug on said front end, a lug on said support for the front end of said front section, and a wedge between said lugs.

14. In a cotton picking machine wherein is provided a main frame around and adjacent which travels an endless slatted spindle carrier on which horizontal rows of spindles having rollers are mounted, said frame having a chamber, there being at least one track for each two horizontal rows of spindles on which track the rollers run: the improvement which includes a sectional member for backing said track, said member including at least a front section and a back section held in longitudinal alignment, a support for the adjacent ends of the sections, an intermediate support for the back section, means to mount said back section on its support for endwise movement of the sections, means limiting the rearward movement of said back section in its supports, and means to support the front section, said last named means including elements on the support for the front end of said front section to hold said front end against up and down movement and limiting its movement toward said track and said carrier, and releasable means constantly urging said front end outwardly toward said track and said carrier, said last named means comprising a lug on said front end, a lug on said support for the front end of said front section, and a wedge between said lugs.
